UNITED STATES PATENT OFFICE.

JOHAN GUSTAF WOLLMAR HINTZE, OF HELSINGBORG, SWEDEN.

DEVICE FOR INSPECTING COMBUSTION IN FURNACES, FLUES, AND THE LIKE.

1,410,181.

Specification of Letters Patent. Patented Mar. 21, 1922.

Application filed September 6, 1919. Serial No. 322,210.

To all whom it may concern:

Be it known that I, JOHAN GUSTAF WOLLMAR HINTZE, a subject of the King of Sweden, residing at Hovidsmansgatan 8, 5 Helsingborg, Sweden, have invented certain new and useful Improvement in Devices for Inspecting Combustion in Furnaces, Flues, and the like, of which the following is a specification.

10 This invention consists of improved devices for use with furnaces or their flues, for enabling the progress or condition, of combustion to be ascertained so that the quantity of air admitted can be regulated as 15 nearly as possible to that theoretically required for proper combustion.

The devices according to this invention provide for the introduction, at any suitable part of a furnace, or furnace flue, of a current of air and the observation of the appearance, or behaviour, of a mixture of such air and the smoke present in the furnace, or flue.

20 In the accompanying drawing a device in accordance with this invention is shown in the wall of a furnace. Figure 1 is a vertical section on the line B—B Figure 4 of the wall with the device in place therein, Figure 2 is a horizontal section on the line 25 A—A Figure 1, Figure 3 shews part of the outer side of the furnace wall and Figure 4 shews part of the inside of the same wall.

30 In the wall *a* (the outer side of which is on the right hand, and the inner side on the left hand, of Figure 1) two blocks *b* and *c* of fire clay, or other suitable material, are introduced. The upper block *b* is provided with a downwardly directed nozzle *d* projecting into the passage-way for the smoke, 35 the opening of said nozzle forming a prolongation of a channel *e* through the block which channel communicates with the open air by means of a channel *f* in the wall *a*.

40 In the outer end of the said channel *f* is a damper *g* preferably consisting of a rotatable plate.

45 The lower block *c*, projects into the passage-way for the smoke and is perforated by an opening *h* funnel shaped at top, the central axis of the said passage and funnel coinciding with that of the mouth of the nozzle. Close below the block *c*, a horizontal channel *i*, extends through the wall *a* the outer end of the said channel *i* being 50 provided with a transparent shutter *k*.

55 When the device is to be used the damper

g is opened, when the chimney draught draws in air in a quantity depending on the position of the said damper. The air passes into the furnace, or flue, through the nozzle *d*, and then passes through the vertical opening *h*, carrying with it a quantity of the smoke after the manner of an injector. The mixture of air and smoke thus obtained and leaving the vertical opening *h* at its lower end, can be observed from without through the shutter *k* and passage *i*.

If carbonic oxide, or other combustible gas, be contained in the smoke, combustion takes place this being indicated by flame at the end of the opening *h*. If, however, no such gas be present, the introduced air only cools the smoke and no flame is formed. From this it can be ascertained whether the combustion in the furnace is proceeding properly, or not, and the quantity of air introduced into the furnace for combustion can be regulated accordingly.

In place of two blocks the device may be formed only of one block provided with the arrangements described.

On the drawing the device is illustrated as being built into the wall *a* but it may, if desired, be loose and be arranged in such a manner that it can be inserted through an opening in the wall and removed therefrom after the observation has been made and the combustion in the furnace has been properly regulated.

It is not essential that the blocks *b*, *c* shall be placed in the relative positions to each other illustrated in the drawing, as they may, in accordance with the direction of the draught be placed in other positions such as side by side, or the block *c* may be placed above the block *b*, and the nozzle *d*, be turned upward.

In place of making the channels *e*, *h*, in blocks of fire clay, or the like, the said channels may be constituted by tubes, the one *f* for the introduction of air being placed in wall *a* and the channel *h* being mounted at the inner end of the tube *f*.

Having now particularly described the nature of my invention and the manner of its operation, what I claim is:

1. In a furnace, flue, or like structure, means for detecting incomplete combustion comprising a wall forming part of the structure and traversed by two channels one of which is adapted to admit atmospheric air, a nozzle at the inner end of the air admis-

sion channel, and an injector element adjacent the nozzle and adapted to co-operate therewith to direct a jet of mixed air and furnace gases past the inner end of the second channel, the said parts being so located that the jet traverses a region of sufficiently high temperature to ignite same if it contains combustible matter.

2. In a furnace, flue, or like structure, 10 means for detecting incomplete combustion comprising a bent nozzle on the inner wall of the structure and communicating with the atmosphere through a channel in said wall, a damper on the outer end of said channel, an injector element in front of the nozzle adapted to direct a jet of mixed air and furnace gases into a region of sufficiently high temperature to ignite the mixture if it contains combustible matter, and 15 an inspection window in said wall so located that the jet can be viewed through the same.

3. A detector of incomplete combustion as claimed in claim 1, comprising a block 25 adapted for insertion into the wall of the structure and containing the air admission channel, and another block also adapted to be inserted into the wall and containing the second channel.

4. A detector of incomplete combustion as claimed in claim 2, comprising a block 30 adapted to be inserted into the wall of the structure and having the channel for admitting atmospheric air to the nozzle, and another block also adapted to be inserted into the wall and containing the inspection 35 window.

In testimony whereof I have affixed my signature in presence of two witnesses.

JOHAN GUSTAF WOLLMAR HINTZE.
